UNITED STATES PATENT OFFICE.

EDWARD NUSSLER, OF DENVER, COLORADO, ASSIGNOR OF ONE-HALF TO AUGUSTUS F. KLASING, OF DENVER, COLORADO.

SAW SET.

Application filed August 7, 1924. Serial No. 730,622.

To all whom it may concern:

Be it known that I, EDWARD NUSSLER, a citizen of the United States, residing at Denver, in the county of Denver and State 5 of Colorado, have invented certain new and useful Improvements in a Saw Set, of which the following is a specification.

My invention relates to improvements in saw-sets.

10 An important object of the invention is to provide a saw-set which is adapted to set a plurality of teeth at the same time, the alternate teeth being set in opposite directions, whereby the complete setting of the 15 teeth is effected by one operation.

A further object of the invention is to provide a device of the above-mentioned character, so constructed that the setting operation is visible.

20 A further object of the invention is to provide a saw-set having detachable setting teeth, whereby the teeth may be employed for saws of different sizes, and also the 25 number of teeth set at the same time may be varied.

25 A further object of the invention is to provide a device of the above-mentioned character, having simple and reliable means for holding the same against slipping movement upon the saw during the setting operation.

30 A further object of the invention is to provide a saw-set having adjustable means to regulate the angular extent of the setting.

35 A further object of the invention is to provide an adjustable gage, whereby the saw-set may be quickly and conveniently shifted the proper distance after each setting operation.

40 Other objects and advantages of the invention will be apparent during the course of the following description.

In the accompanying drawings forming a 45 part of this specification, and in which like numerals are employed to designate like parts throughout the same.

Figure 1 is a plan view of a saw-set and gage embodying my invention;

Fig. 2 is a side elevation of the same;

Fig. 3 is an edge elevation of the same;

Fig. 4 is a similar view, with parts in central vertical section, taken on line 4—4 of Fig. 1;

Fig. 5 is a vertical section taken on line 55 5—5 of Fig. 4.

Fig. 6 is a detail horizontal section taken on line 6—6 of Fig. 3;

Fig. 7 is a central longitudinal vertical section through the adjustable gage;

Fig. 8 is a transverse section taken on line 60 8—8 of Fig. 7; and

Fig. 9 is a perspective view of one of the setting teeth carrying plates.

In the drawings, wherein for the purpose of illustration is shown a preferred embodiment of my invention, the numeral 10 designates a lower handle, having its forward end provided with a fork 11, forming a relatively large opening 12. This fork is provided with upstanding knuckles 13, from which depend a forward jaw 14, rigidly secured thereto. Arranged above the lower handle 10 is an upper handle 15, provided at its forward end with a fork 16 carrying knuckles 17. The knuckles 17 are arranged 70 within the knuckles 13, and are pivotally connected therewith by pins 18 or the like. The fork 16 provides a large opening, leading into the opening 12. Depending from the knuckles 17 and formed integral therewith is a rear jaw 19, disposed opposite the forward jaw 14. Formed integral with the lower ends of the jaws 14 and 19, are inwardly facing sockets 20, receiving resilient clamps 21, formed of rubber or like material. These clamps are adjusted by means of screws 22, engaging within screw-threaded openings 23. The extent of inward movement of the handles 10 and 15 is regulated 75 by an adjustable set-screw 24, engaging within a screw-threaded opening 25', and contacting with the upper lever 15, as shown.

Formed upon the inner faces 14 and 19 are recesses 24 (see more particularly Fig. 6) 80 for the reception of setting teeth carrying plates 25, which are detachably held within these recesses by means of screws 26 or the like. The plates 25 are provided at their 85 opposite ends with setting teeth 27. As more clearly shown in Fig. 1, the teeth on one plate are arranged to enter the spaces between the teeth of the opposite plate, and these two sets of teeth carried by the upper ends of the plates will set a plurality of 90 saw teeth, the alternate saw teeth being set in opposite directions. It is obvious that the plates 25 may be readily removed from within the recesses, and inverted, whereby 95 the setting teeth at their opposite ends may 100

105 110

be employed. It is also obvious that the plates may be entirely removed and other plates substituted therefor, having setting teeth of different sizes or character, depending upon the size and character of the saw teeth to be set.

I provide an adjustable gage, to regulate the extent of movement of the saw-set, at the end of each setting operation. This 10 gage embodies a body portion or block 28, which may be formed of wood or the like, and provided in its lower edge with a groove 29, to receive the teeth of the saw 30. A 15 wear plate 31, formed of metal or the like, is preferably located at one end of the slot 29, and a vertical metal plate 32 is secured to the opposite end of the body portion or block 28, by screws 33 or the like. This metal plate serves as a stop, and has a beveled tooth 34, extending downwardly below the top wall of the slot, and engaging behind the saw teeth. The stop plate has an opening 35, loosely receiving the screw-threaded portion of a rod 36, having a 20 downwardly bent end 37, but has no screw-threaded engagement with this portion, which is free to reciprocate therein. A nut 38 is carried by the screw-threaded portion of the rod 36, within a recess 39, and an 25 adjustable thumb nut 40 engages the screw-threaded portion of the rod, outwardly of the stop plate 32. The downwardly bent end 37 is adapted for insertion within an opening formed in the ear 41, rigidly secured to the fork 11, as shown.

In the use of the device, the thumb-nut 40 is first adjusted, for effecting a proper distance between it and the stop plate 32, depending upon the distance occupied by 40 the number of saw teeth which are set at one time. This having been properly determined, the body portion or block 28 is arranged upon the saw teeth, with the tooth 34 between a pair of selected teeth. The 45 saw-set may now be moved the maximum distance from the body portion 28, spaced upon the saw, with the teeth 27 engaging the saw teeth to be set. The handles 10 and 15 are now brought together, by the 50 operator squeezing them in his hand. The resilient elements 21 first grip the saw, so that the set cannot slip thereon, and subsequently the teeth 27 set the saw teeth. While the saw-set is clamped to the saw, 55 the operator may shift the block 28 toward the saw-set, until the stop plate 32 contacts with the nut 40, and can hold this block to the teeth. The saw-set may be released from the teeth of the saw, and then shifted 60 from the block 28, until the nut 38 contacts with the stop plate 32, at which time the saw-set will be in the proper position to set the next set of teeth. This operation may continue, as is obvious.

An important feature of the invention is

the provision of the openings in the forks of the handle, which permit of the setting operation being visible at all times.

It is to be understood that the form of my invention herewith shown and described is to be taken as a preferred example of the same, and that various changes in the shape, size, and arrangement of parts may be resorted to without departing from the spirit of my invention or the scope of the subjoined claims.

Having thus described my invention, what I claim is:

1. A saw-set comprising a pair of handles which are directly pivotally connected and 50 carry laterally extending jaws having recesses, plates reversibly mounted within the recesses and having setting teeth at their opposite ends, and means to prevent the saw-set from slipping upon the saw. 55

2. A saw-set comprising a pair of handles which are directly pivotally connected and carry laterally extending jaws provided upon their inner faces with recesses, and plates removably mounted within the 60 recesses, said plates being provided at their opposite ends with setting teeth. 65

3. The combination with a saw-set to be adjusted longitudinally of the saw, of a member to be held upon the saw at a selected position, and a sliding connection between the saw-set and member to permit of a limited selected movement of the saw-set 70 longitudinally of the saw. 95

4. The combination with a saw-set to be adjusted longitudinally of the saw, of a member to be held upon the saw at a selected point, an element having slidable connection with the member to move longitudinally thereof and connected with the saw-set, and stop means adjustable longitudinally of said element. 100

5. A saw-set comprising a pair of handles having forks at their forward ends, means for pivotally connecting the forks, a pair of jaws rigidly secured to the forks and arranged at approximately a right angle to the handles, the tops of the jaws being visible through the openings formed within the forks, saw-setting teeth carried by the jaws and visible through said openings, sockets rigidly secured to the lower ends of the jaws, and resilient clamping elements held within the sockets. 110

6. A saw-set comprising a pair of handles having forks at their forward ends, means for pivotally connecting the forks, a pair of jaws rigidly secured to the forks and arranged at approximately a right angle to the handles, the tops of the jaws being visible through the openings formed within the forks, saw-setting teeth carried by the jaws and visible through said openings, sockets rigidly secured to the lower ends of the jaws, resilient clamping ele- 120

125

130

ments held within the sockets, and adjusting elements engaging the clamping elements.

7. A saw-set comprising a pair of handles, means for pivotally connecting the handles, a pair of jaws rigidly secured to the handles and extending laterally therefrom and arranged in opposed relation, saw-setting teeth carried by the jaws near their upper ends, sockets carried by the jaws near their lower ends, rubber clamping elements within the sockets, and screws engaging the sockets and the rubber clamping elements.

8. A saw-setting implement adapted to be bodily held in the hand, comprising a

pair of handles provided at their forward ends with forks, one fork fitting within the other, means pivotally connecting the forks, oppositely arranged jaws carried by said forks and extending laterally therefrom, the tops of the jaws being visible through the openings formed by said pair of forks, saw-setting teeth carried by the jaws, and resilient clamping elements attached to the jaws outwardly of the saw-setting teeth and adapted to engage with opposite faces of the saw.

In testimony whereof I affix my signature.

EDWARD NUSSLER.
